UNITED STATES PATENT OFFICE.

CHARLES WILLIAM WEIGHTMAN, OF CARLISLE, PENNSYLVANIA, ASSIGNOR OF ONE-HALF TO JOHN ALLOWAY MCCLAIN, OF CARLISLE, PENNSYLVANIA.

MANURE SPREADER.

1,425,729.

Specification of Letters Patent. Patented Aug. 15, 1922.

Application filed December 19, 1921. Serial No. 523,509.

To all whom it may concern:

Be it known that I, CHARLES W. WEIGHTMAN, a citizen of the United States of America, and resident of Carlisle, in the county of Cumberland and State of Pennsylvania, having invented certain new and useful Improvements in Manure Spreaders, of which the following is a specification.

This invention relates to manure spreaders, and particularly to an attachment adapted to be applied to a spreader which will prove effective to maintain the driving chain of such mechanism in operative engagement with the driving wheel which, in these devices, is usually in the nature of a sprocket wheel, novel means being also provided for disengaging the chain from the driving wheel when that is desirable or necessary.

It is a further object of this invention to produce a mounting for one of the sprocket wheels of the driving chain well below the plane of the top of the periphery of the driving wheel, in order that a greater number of links of the driving chain will be in engagement with the teeth of the driving wheel, a condition which prevents jumping of the chain, even though the spreader is traveling over rough surfaces.

It is a still further object of this invention to provide an arm which is oscillatably mounted with respect to a driving chain, the said arm having an angularly disposed or curved portion which extends downwardly, in order that a spring action will result at the angularly disposed or curved portion. The mounting also maintains the parts in operative relation and in effective working condition, even though the driving chain has become stretched, so that by this invention the usefulness of the parts is prolonged and their efficiency is increased.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote correspond-

ing parts in the several views, and in which—

Figure 1 illustrates a view in elevation of the driving distributor or feed drive of a manure spreader; and

Figure 2 illustrates a perspective view of the mounting for the sprocket chain.

In these drawings 5 denotes the drive wheel, 6 the drive chain, 7, 8, 9, and 10 sprocket wheels with relation to and in engagement with which the drive chain works. The parts just described are of conventional type and the description of them need not, it is thought, be enlarged in order that one skilled in the art may understand the application and use of the invention.

The arm 11 has an aperture 12 to receive a stud or pivot 13 so that said arm may oscillate and be moved under the influence of the rod 14 which is connected to a depending portion 15 of the lever through the hole 16. The arm 11 extends downwardly as indicated at 17 and is provided with an extension 18 on which the sprocket wheel 10 is carried. It has been found in practice that the arm will spring perceptibly at or near the point where it extends downwardly at 17 and this springing action serves to relieve jar and strain on the chain without, however, impairing the successful operation of the device.

Through the operation of the rod 14, the arm may be oscillated to change the position of the sprocket wheel 10 with relation to the drive wheel 5, in order that a comparatively great number of links of the chain will be caused to engage the teeth of the drive wheel, or, if desired, the arm can be swung upwardly to entirely disengage the chain from the drive wheel, so that provision is made for a wide range of movement of the arm under the influence of the rod.

The arm of this character can be installed on spreaders now in common use and it will increase the efficiency and durability of the drive chain and parts associated with it; furthermore, the arm is of comparatively inexpensive production in that it can be formed wholly by the stamping process.

I claim:

In a drive mechanism for manure spread-

ers, a drive wheel, a drive chain adapted to engage the periphery of the drive wheel for operating the distributor or spreader, an arm oscillatively mounted above the drive wheel, means connected to the arm on one side of the pivot for oscillating the arm, the said arm having a depending portion and an extension on the other side of the pivot,

the said depending portion having a spring action with relation to the drive wheel, and 10 a wheel rotatably mounted on the extension of the arm engaged by the drive chain and adapted to move the drive chain toward and away from the drive wheel as the said arm is oscillated.

CHARLES WILLIAM WEIGHTMAN.
